ROTARY MOTOR.

No. 876,396.

Specification of Letters Patent.

Patented Jan. 14, 1908.

Application filed October 7, 1904. Serial No. 227,600. Renewed June 3, 1907. Serial No. 377,048.

To all whom it may concern:

Be it known that I, JOHN C. REUTER, a citizen of the United States, residing at New York, in the county of New York and State 5 of New York, have invented a new and useful Rotary Motor, of which the following is a specification.

This invention relates to a rotary motor of that type which is characterized by a cylinder inclosing an epicyclic or planet piston journaled on the crank of an engine shaft which latter is co-axial with the cylinder.

Among the various objects of the invention the most prominent are as follows: 15 first, to provide a motor which will develop a maximum efficiency for a given unit of weight and with a minimum expenditure of fuel; second, to economize the expenditure of motive fluid in a motor of this type by utilizing said fluid expansively by a cut-off of the direct supply after a given travel of the piston under direct pressure; third, to still further economize the expenditure of the motive fluid by compounding the latter through 20 the medium of mechanism whereby, after the fluid has been used directly and expansively against a given area of a piston, will be exhausted and redirected against the piston at another point; fourth, to provide for 25 reversing the motor and for varying the lead of the controlling valve by the manipulation of a single controlling lever; fifth, to provide novel anti-frictional means for dividing the cylinder of the motor into a plurality of compartments to which the motive fluid is successively led; sixth, to provide a motor of 30 this type with a novel exhaust valve by means of which the motive fluid is led from each compartment of a cylinder, after being used directly and expansively therein, to another compartment for compound use and whereby the first compartment, having been substantially exhausted, will be placed in communication with the outer air and thus 35 completely cleared for the purpose of preventing back pressure; seventh, to improve the construction of the epicyclic piston for the purpose of precluding the possibility of leakage, and to render the operation of the 40 same substantially anti-frictional; eighth, to provide for the simultaneous operation of the controlling and reversing valves of the motor, and the water and kerosene supply valves, by means of a single lever, the manipulation of which serves to stop, start, or

reverse the motor or to increase or diminish the supply of motive fluid for the purpose of controlling the speed of operation.

Subordinate to the recited objects are others, which will appear as the succeeding 60 description of the illustrated embodiment of the invention is developed.

In the accompanying drawings—Figure 1 is a central longitudinal section of the motor complete, certain of the parts being shown in 65 elevation. Fig. 2 is a transverse section on the line 2—2 of Fig. 1. Fig. 3 is a section on the line 3—3 of Fig. 1, but viewed from the opposite direction. Fig. 4 is a transverse section on the line 4—4 of Fig. 1, being designed more particularly to show the arrangement of the controlling and reversing valves. Fig. 5 is a sectional view of the vaporizing chamber and the vaporizer. Fig. 6 is a detail sectional view, showing the arrangement of a motive fluid inlet or supply port. Fig. 7 is a detail view of a portion of the reversing mechanism. Fig. 8 is a sectional end elevation of the vaporizing chamber and as 70 associated parts. Fig. 9 is a detail view of one 75 of the spray nozzles. Figs. 10 and 11 are detail views of the controlling valve. Fig. 12 is a similar view of the reversing valve. Figs. 13 and 14 are detail views of the exhaust valve.

Like numerals are employed to designate corresponding parts throughout the views.

Supported by a suitable base 1, and preferably cast integral therewith, is a cylindrical shell 2 constituting the motor cylinder and closed at its opposite ends by heads 3 and 4 retained in any suitable manner. Through these heads is passed an axial motor shaft 5 provided within the cylinder with a crank 6 upon the wrist 7 of which is anti-frictionally 90 retained an epicyclic or planet piston 8 which rolls against the inner face of the cylinder, and thus rotates upon the wrist of the crank which is carried with said piston to rotate the shaft as the piston revolves around 95 the axis of the cylinder.

The piston 8 is constructed in two sections 9 and 10, the outer section 9 having the form of a cylinder extending entirely across the engine cylinder, and the inner section being likewise of cylindrical form and corresponding in length with the length of the wrist 7. Both the inner and outer sections of the piston are hollowed out for the sake of lightness and within the inner section is fitted a wear sleeve 110

11 between which and the wrist are interposed a series of anti-frictional elements, preferably in the form of rollers 12. In the opposite end faces of the piston section 9 are 5 formed annular grooves or channels 13 designed for the reception of rollers 14 extending inwardly from the inner ends of wear plates 15 secured to the opposite ends of partitions 16, 17 and 18. These partitions, as 10 shown in Figs. 3 and 4, are three in number and are disposed radially with respect to the axis of the engine cylinder, and while the piston is designed to rotate independently of the partitions, a fluid tight joint is maintained 15 between the periphery of the piston and each partition by means of a yielding packing block 19, of Babbitt metal or other suitable material, retained in a recess 20 in the inner edge of the partition and urged into close contact with the piston by a spring 21, as shown 20 in Fig. 1.

The partitions 16, 17 and 18 maintain at all times their radial disposition, and, as they are designed to remain in close contact with 25 the periphery of the piston during the epicyclic movement of the latter, they must necessarily reciprocate toward and from the axis of the motor. The partitions are guided in their reciprocatory movement by radial ways 30 or guide grooves 22, formed in the opposed faces of the heads 3 and 4 and receiving the wear plates 15 secured to the opposite ends of the partitions. To accommodate the partitions the cylinder is formed with radial 35 pockets 23 alined with the ways 22 and closed at their opposite ends by detachable plates 24 constituting removable sections of the cylinder heads 3 and 4. If desired, these removable end walls or plates 24 for the pockets 23 may be formed integral with the cylinder heads, but they are preferably detachable as shown, in order to facilitate access to the 40 pockets for purposes of inspection and repair without necessity for extensively dismantling 45 the motor.

The engine cylinder 2 is extended beyond the inner heads 3 and 4 to what may be termed the outer heads 25 and 26 retained in place by tie-rods 27, and constituting 50 the outer walls of valve chambers 27 and 28 within which are located the supply and exhaust valves 29 and 30. It will now be noticed, by reference to Fig. 2, that the partitions 16, 17 and 18, connected at their inner ends by the piston 8, subdivide the cylinder into three compartments, which, for convenience of description, will be designated A, B and C. Each of these compartments is provided with two supply ports 55 located adjacent to its opposite ends, those of compartment A being denominated A' and A², those of compartment B, B' and B², and those of compartment C, C' and C². Each of these ports is formed in the wall of 60 the cylinder and opens at its opposite ends 65

into the chambers of the supply and exhaust valves and also opens at an intermediate point into the cylinder. This arrangement of the ports will be clearly understood by reference to Figs. 1 and 6, it being noted 70 that the opening 31, which places each of the supply ports in communication with the interior of the cylinder, extends substantially the entire distance between the heads 3 and 4, although this opening may be more 75 restricted if desired. While each of the cylinder compartments is provided with two supply ports, as stated, one port only of each compartment is designed for use when the engine is running in a given direction, the 80 duplication of course being made necessary in order to permit the reversal of the motor. In order, therefore, to provide for the closing of one series of supply ports, that is to say, one port for each compartment, I mount 85 within the chamber 28 what may be termed a reversing valve 32, see Figs. 1, 4, 6 and 12. The reversing valve 32 is in the form of a disk rotatably mounted on the shaft 5 immediately adjacent to the head 4 and having an 90 annular flange 33 opposed to the peripheral wall of the chamber 28 and having three openings 34, 35 and 36, which, according to the position of the valve 32, are brought in apposition with the ports A', B' and C', or 95 the ports A², B² and C². In other words, by means of this reversing valve 32 one series of supply ports are opened and the other closed, accordingly as it is desired to operate the motor in one direction or the 100 other. To effect the necessary change in position of the reversing valve, it is designed to be shifted on the shaft 5 as an axis, but the mechanism whereby this operation is effected will be described later. It will be 105 assumed, however, for the present that the reversing valve 32 is in the position shown in Fig. 4, the openings therein being opposite the ports A', B' and C', and constituting 110 continuations thereof in effect. The motive 115 fluid is designed to be admitted to these ports from the chamber 27 in successive order and the control of the supply is effected by the valve 29, heretofore referred to as being located within the chamber 27.

The valve 29, like the reversing valve 32, is in the form of a disk which is provided with an annular flange 37 opposed to the inner face of the flange 33 of the controlling valve and provided with a slot 38 extending around approximately one-third of the valve. As this controlling or supply valve 29 normally rotates with the engine shaft, the slot 38 will be presented opposite the supply ports in succession and will maintain the 120 communication between a given port and the source of motive fluid supply for a considerable interval, that is to say, for a period of piston travel corresponding with the 125 length of the slot 38. Of course, when the 130

reversing valve is shifted to close the supply ports A', B' and C' and to open the ports A², B² and C², for the purpose of reversing the engine, the controlling valve 29 must be shifted relative to the piston in order to cause the slot 38 in said valve to move opposite the ports at the proper times, notwithstanding this reversal of normal conditions. It is desirable, however, that the normal 10 operation of the engine be fully understood before these various arrangements for its reversal are considered, and therefore, before describing the mechanism for shifting the controlling valve to accommodate the reversal of the engine, I will pass to a consideration of the mechanism whereby the motive fluid, having operated directly and expansively on the piston, is used over again before being finally exhausted.

20 It will be noted, by reference to Fig. 2, that the partitions and piston serve to divide the interior of the cylinder into three distinct compartments. These compartments are identical, both in proportion, and in 25 equipment for the supply and exhaust of the motive fluid. I will, therefore, first describe the operation of the engine during the traverse of one compartment by the piston and will then attempt to make plain 30 the manner in which the several compartments are related one to another in the operation of the motor.

In the position of the parts shown in Fig. 2, the piston has just arrived at a position 35 where it may be effectively propelled by the admission of motive fluid to the upper end of the compartment A through the supply port A', and as a matter of fact, is being propelled by motive fluid so admitted. This 40 initial admission of motive fluid to the compartment is, however, in the form of exhaust from another compartment, it being observed that the compartment A cannot be supplied directly from the chamber 28 for 45 the reason that the slot 38 in the controlling valve has not yet reached a position opposite the port A', see Fig. 4. Therefore, the initial movement of the piston in the compartment A will be effected by the admission of 50 exhaust fluid to said compartment from another compartment, to-wit, the compartment C, and after a predetermined piston travel, to-wit, from the position shown in Fig. 2 to that shown in Fig. 3, the supply of 55 exhaust fluid to the compartment A will have been cut off in a manner to be hereafter described, and a supply of like fluid will then be furnished from the chamber 28 since the controlling valve will now have moved sufficiently to open the port A'. The piston will 60 now continue its movement until it reaches a position in compartment B corresponding to its present position in compartment A, a portion of this movement being effected 65 by the use of the motive fluid expansively

for the reason that the valve 29 will have closed the port A' before the piston reaches that position in compartment B which corresponds with its present position in compartment A. Having reached said position, however, 70 the motive fluid will be exhausted from compartment A and into compartment B by way of the port B', and as the piston traverses the compartment B, a repetition of the described operation will take place, 75 That is to say, the piston will be moved first by the admission of fluid exhausted from another compartment, next under direct pressure, and finally by the use of the fluid expansively.

We have seen that the direct admission of the fluid to the compartments is controlled by the valve 29, the slot or opening 38 in which is brought successively in apposition to the ports A', B' and C' to admit 80 motive fluid directly from the chamber 28 to the several compartments A, B and C in successive order. I will now describe the instrumentality whereby the motive fluid, having been used directly and expansively, 85 in one compartment, is automatically supplied to the next compartment to effect the initial movement of the piston therein, and the provision which is made for finally exhausting or clearing each compartment to 90 avoid back pressure.

The head 3 of the cylinder 2 is provided with three exhaust ports A³, B³, and C³, one for each compartment and in equidistant relation. At the outer side of the head 3, 100 to-wit, in the chamber 28, is located the combined exhaust and compounding valve 30 having the form of a hollow disk keyed to the motor shaft 5 and provided with a partition 39 subdividing the interior of the 105 valve into two compartments 40 and 41. The compartment 40, which may be known as the compounding compartment of the exhaust valve, is closed, with the exception of two openings or ports 42 and 43 opening 110 through the periphery of the valve, and two diametrically opposed ports 44 and 45 in the side wall of the valve nearest the head 3 of the cylinder 2 and arranged to be brought into apposition with the exhaust ports A³, 115 B³, and C³, in a manner to be described. Each side wall of the other or exhaust compartment 41 of the valve 30 is provided with a long arcuate slot 46, likewise arranged to come opposite the exhaust ports 120 of the cylinder. The construction of the valve 30 is clearly shown in Figs. 1, 13 and 14 and its relation to the various ports of the motor is clearly indicated in dotted lines in Fig. 2. It will be noted, by reference to the latter figure, taken in connection with Fig. 13, that the port 44 and the combination valve 30 is opposite the exhaust port C³ of the motor compartment C, that the port 42 in the periphery of the valve is in partial ap- 130

position to the supply port A', and that the slots 46 in the valve are opposite the exhaust port B³ of the compartment B, attention being further directed to the fact that the 5 peripheral port 43 is opposite and closed by the wall of the cylinder, that the side port 45 of the valve 30 is opposite and closed by the head 3 of the cylinder, and that the exhaust port A³ of the compartment A is cov- 10 ered and closed by the piston 8.

We may now understand more clearly the 15 operation of the motor, since it will be evident that the right hand ends of all of the supply ports will be closed by the controlling valve 29, see Fig. 4, and that the left hand ends of all of said ports will be likewise closed, with the exception of the port A', which, as we have seen is in partial opposition with the peripheral port 42 of the controlling valve.

20 The motive fluid, which has now performed its function in the compartment C of the motor, will escape through the exhaust port C³ and valve port 44, into the compounding compartment 40 of the valve 30 from whence 25 it will escape by way of the port 42 and the supply port A' to the upper end of the compartment A. The exhaust fluid from the compartment C being thus liberated within a chamber defined by the partition 16, the 30 periphery of the piston, and the wall of the cylinder, will expand against the partition and cylinder which constitutes a fixed abutment and necessitate the movement of the piston. As heretofore stated, this continues 35 until the port 42 of the combination valve has moved entirely past the supply valve A', when, as will be evident, the supply of exhaust fluid to the compartment A from the compartment C will cease and the compartment A will be supplied with high pressure 40 fluid from the chamber 28 by the opening of the right hand end of the port A' by the controlling valve 29.

It will, of course, be understood, that the 45 compartment C is not entirely depleted by its communication with the compartment A, since the communication is necessarily cut off long before the pressure in the compartment C has been reduced to atmospheric. It 50 is therefore desirable to completely exhaust or clear the compartment C as soon as the communication between the compartments C and A has been cut off by the movement of the combination valve 30. This end is at- 55 tained by the provision of the slots 46 in the valve 30, since it will appear by further reference to Fig. 2, that when the combination valve 30 has moved sufficiently to carry the port 42 thereof beyond the supply port A', 60 the slot 46 will move to a position opposite the exhaust port C³ of the compartment C, thus permitting the motive fluid remaining in said compartment to escape to the exhaust chamber 41 of the valve 30 and thence to 65 the exhaust chamber 28 which is in com-

munication with the outer air by way of an exhaust pipe 46. This will be better understood by reference to the position of the parts shown in compartment B, which in the present position of the engine is cleared. 70 Thus, to recapitulate briefly; the upper end of the compartment A in Fig. 2 is receiving the exhaust fluid from the compartment C and the compartment B is completely exhausted.

When the piston reaches the position shown 75 in Fig. 3, the compartment A will take high pressure fluid directly from the chamber 28 and the compartment C will be cleared. The piston will now continue to advance under high pressure, but before the port 42 in the 80 periphery of the combination valve 30 reaches the supply port B' of the compartment B, the controlling valve will have closed the right hand end of the supply port A', thus cutting off the supply of high pressure fluid 85 to the compartment A. After this automatic cut-off is effected, the motive fluid in the compartment A is used expansively until the port 42 of the valve 30 reaches the supply port B' of the compartment B, when, as will 90 be evident, the piston will have covered the exhaust port A³ of the compartment A and the fluid will be exhausted from said compartment to the compartment B by way of the port A³ in the cylinder, the ports 44 and 95 42 of the valve 30, and the supply port B'. The piston will then be advanced across the compartment B in the manner described in connection with its advance across compartment A, said compartment first taking the 100 exhaust fluid from another compartment, next taking high pressure fluid from the chamber 28, next permitting the advance of the piston by the expansion of the fluid, next exhausting into another compartment, and finally being completely exhausted or cleared. 105 For the purpose of relieving compression in the pockets 23 above the partitions, the top wall of each pocket is provided with a vent 47 controlled by a needle valve 48, and in 110 order that any motive fluid escaping into the pocket around the partition may be discharged from the motor, an exhaust passage 49 is led from the vent 47 to the chamber 28, see Fig. 1.

115 The foregoing constitutes a description of a complete embodiment of my invention, viewed in its broader aspect, since it is capable of being operated by a motive fluid supplied to the chamber 27 from any suitable 120 source, and since without further addition, the engine is capable of practical operation in one direction. I shall now proceed, however, to describe a further development of the invention, having for its object the provision of means whereby the engine may be reversed at the will of the operator.

125 We have already seen that each of the motor compartments A, B and C is equipped with two supply ports. The arrangement of 130

each is identical except that said ports are located adjacent to opposite ends of a compartment. We have also seen that the reversing valve 32 is designed to open one series and close the other, so that, taking the compartment A as an example, the motive fluid will be supplied to the lower end of the compartment instead of to the upper end thereof, as is the case when the piston is moving in the direction indicated by the arrow in Fig.

2. It will now be observed that if the reversing valve 32 is shifted so as to close the right hand ends of the supply ports A', B' and C', and open the ports A², B² and C², and the controlling valve 29 is shifted so that the slot therein will bear the same relation to the open ports that it formerly bore to the ports which are now closed, the engine will operate precisely in the manner heretofore described, but in the reverse direction, since the functions heretofore performed by the ports 44 and 42 of the combination valve 30 in connection with the ports A', B' and C', will now be performed in the reverse operation of the motor by the valve ports 45 and 43 in connection with the supply ports A², B² and C².

While many forms of mechanism may be utilized for the shifting of the controlling and reversing valves to reverse the motor, I have shown a simple arrangement whereby both of these elements may be shifted simultaneously, though in different degree, by the manipulation of a single lever. The controlling valve 29 is provided, as shown in Fig. 1, with a comparatively long hub 50 encircling the shaft 5 and extended outwardly through a stuffing box 51 screwed through an axial opening in the head 25. To the outer end of the hub 50 of the controlling valve is secured by any suitable means, as for instance, a set screw 52, a sleeve 53 provided with a pair of cam slots 54 for the reception of rollers 55 carried by a sliding collar 56, splined on the shaft 5 to compel its rotation therewith, and extended into the sleeve 53. As longitudinal movement of the collar 56 is obviously essential to the relative rotary movement of the shaft 5 and the sleeve 53, it follows that the normal retention of the collar against movement longitudinally of the shaft will compel the controlling valve to rotate with the shaft as the latter rotates. To effect the shifting of the controlling valve 29 relative to the shaft when the reversal of the motor is desired, it is simply necessary to shift the collar 56 longitudinally on the shaft, when, as will be evident, the engagement of the rollers 55 with the slots 54 will compel the cylinder 53 and the valve 29 fixed thereto to rotate on the shaft. I therefore provide the outer end of the collar 56 with the circumferential groove 57, engaged by a pin 58 extending laterally from a controlling lever 59 suitably fulcrumed at a point above the collar 56 and provided with a spring latch 60 engaging

a toothed segment 61 to retain the lever in its adjusted positions. Normally, the lever stands in the position shown in Fig. 1, but, when it is desired to reverse the engine, the handle of the lever is moved to the left, thus causing the collar 56 to be drawn to the right and reversing the position of the controlling valve 58 in an obvious manner.

In order to shift the reversing valve 32 whenever the controlling valve is shifted in the manner described, I extend the lower end of the lever 59 beyond the collar 56 and attach to its extremity a connecting rod 62, which is in turn connected to the long arm of a bell-crank lever 63 fulcrumed on a suitable bracket 64 extending from the head 25, or any other fixed part. The short arm of the lever 63 is bifurcated for the reception of a crank arm 65 extending laterally from the outer end of a horizontal shaft 66 extended through a bearing sleeve 67 in the head 25, and provided with a suitable gland 68 to insure a fluid tight joint, preventing the escape of the motive fluid around the shaft 66 from the chamber 28. To the inner end of the shaft 66 is secured a rocker 69 engaging a recessed lug 70 projecting upwardly from the outer edge of the reversing valve flange 33, see Figs. 1 and 12. Thus, when the lever 59 is shifted to reverse the position of the controlling valve 29, the bell-crank lever 63 will be simultaneously swung to rock the shaft 66 and thus cause the rocker 69 to shift the reversing valve 32 to move the ports 34, 35 and 36 therein from the ports A', B' and C' to the ports A², B² and C². Furthermore, by this connection of the controlling lever 59 with the controlling and reversing valves, it is possible not only to control the direction of rotation of the engine, but also the speed of the latter, since by comparatively slight movement of the lever, the lead of the controlling valve may be changed to vary the points of cut-off, and since the movement thus imparted to the reversing valve, while insufficient to close the supply ports, will reduce the area of their open ends. This latter peculiarity also makes it possible to economize the expenditure of motive fluid by varying the port areas in accordance with the load under which the motor is operated.

Opposite an opening 71 in the head 25 is secured a retort 72 inclosing a heater 73. Oil and water pipes 74 and 75 are extended into the retort and equipped with spray nozzles 76 and 77 from which oil and water are sprayed against the vaporizer. Each nozzle is equipped with a conical deflector 78 surrounded by a flared passage 79 having spray apertures 80 in its bottom wall. The pipes 74 and 75 are supplied from water and oil tanks 81 and 82. The supply is controlled by valves 83 and 84 having operating arms 85 and 86 connected to the lever 59 by 130

rods 87, which, as we have already seen, is operatively connected to the supply and reversing valves of the motor. The vaporizer 73 is of refractory material and incloses 5 heating coils 88 screwed upon a plug 89 retained by a nut 90, the plug and nut being separated from the wall of the retort by insulation 91. The feed wires *a* and *b* for the heating coils are connected to the posts of a 10 dynamo 92 operated in any suitable manner. The lever 59 is fulcrumed on the plug 89 as indicated at 83, the plug also constituting a support for the rack 61 provided with an eye 94 surrounding the plug. In addition 15 to the water and oil, air is supplied to the retort under pressure from a tank 95 through an air supply pipe 96 containing a globe valve 97. The air pipe is led to an air dome 98 containing a spring pressed air valve 99.

20 Obviously, a motor constructed in accordance with my invention is adapted for general application as a power generator, regardless of the character of work to be performed or of the specific nature of the motion transmitting mechanism employed in connection therewith. Furthermore, the invention in its broader aspects comprehends a motor construction capable of being operated by any expansive fluid, as for instance, steam 25 or compressed air, although it is preferred, as heretofore stated, to operate the motor by the expansive force of a fluid composed of kerosene vapor and steam.

It is thought that from the foregoing the 35 construction and operation of my motor will be fully comprehended; but, while the present embodiment of the invention appears at this time to be preferable, I wish to be distinctly understood as reserving the right 40 to effect such changes, modifications and variations of the illustrated structure as may come fairly within the scope of the protection prayed.

What I claim is:—

45 1. In a rotary motor, the combination with a cylinder and a motor shaft having a crank therein, of an epicyclic piston mounted on the crank and comprising inner and outer cylindrical members, and sliding partitions 50 connected to the outer piston member, said outer member being of sufficient dimensions to permit the withdrawal of the inner member and the crank.

55 2. In a rotary motor, the combination with a cylinder provided with radial grooves and pockets, of an epicyclic piston within the cylinder, a series of partitions, wear plates 60 detachably connected to the ends of the partitions and received within the grooves in the cylinder, means for operatively connecting the inner ends of the wear plates with the piston, whereby said piston effects the reciprocation of the partitions, and wear blocks 65 mounted in the partitions and engaging the periphery of the piston.

3. In a rotary motor, the combination with a cylinder and a motor shaft provided with a separable crank located therein, of a cylindrical piston mounted on the pin of the crank and comprising separable inner and outer members, the outer member being of sufficient dimensions to permit the withdrawal of the inner member therefrom, whereby the motor crank may be removed without disorganizing the piston or the shaft, 75 and the inner piston member removed without disturbing the outer piston member.

4. In a rotary motor, the combination with a cylinder and a motor shaft having a crank therein, of an epicyclic piston mounted on the crank and comprising inner and outer cylindrical members, a wear sleeve within the inner member, and a series of rollers interposed between said wear sleeve and the pin of the crank.

5. In a rotary motor, the combination with a cylinder provided with radial pockets and heads, of sliding partitions movable into the pockets, a piston co-operating with the partitions, and detachable end plates closing 90 the ends of the pockets and constituting separable extensions of the heads.

6. In a rotary motor, the combination with a cylinder provided with separate, detachable, inner and outer heads spaced apart 95 to form supply and exhaust chambers, and tie-rods extending between the outer heads to draw the same in close contact with the ends of the cylinder.

7. In a rotary motor, the combination 100 with a cylinder provided at its opposite ends with circular supply and exhaust chambers, exhaust ports opening into the exhaust chamber from the cylinder, supply ports opening into the supply chamber through the peripheral wall thereof and leading into the cylinder, supply and exhaust valves located in the supply and exhaust chambers, and a piston in the cylinder.

8. In a rotary motor, the combination 110 with a cylinder having supply and exhaust chambers at the opposite ends thereof, supply ports extending from the peripheral wall of the supply chamber to the interior of the cylinder, and exhaust ports opening into the 115 exhaust chamber through one head of the cylinder, supply and exhaust valves located in the chambers, a piston within the cylinder, and means for operating the valves from the piston.

9. In a rotary motor, the combination with a cylinder having a supply chamber at one end thereof and supply and exhaust ports, of a piston in the cylinder, a motor shaft operated by the piston, a controlling valve located in the supply chamber and operated from the piston, said valve being shiftable relative to the piston to change its lead and means for holding the valve against movement relative to the piston, whereby a 130

variation of the lead can be obtained without reversal of the motor.

10. In a rotary motor, the combination with a cylinder provided with supply and exhaust chambers at its opposite ends and with supply and exhaust ports, of a piston in the cylinder, piston operated supply and exhaust valves located in the chambers, and means for shifting the supply valve to change the lead thereof.

11. In a rotary motor, the combination with a cylinder having supply and exhaust ports, of a piston in the cylinder, and a rotary supply valve controlling the supply ports and operated by the piston, said valve having the form of a disk provided with an apertured annular flange.

12. In a rotary motor, the combination with a cylinder provided with exhaust ports and with separate sets of supply ports, of an epicyclic piston within the cylinder, a supply valve common to all of the supply ports, and means for closing one set of ports and opening another to effect the reversal of the motor.

13. In a rotary motor, the combination with a cylinder provided with a supply chamber and with separate sets of supply ports leading to the interior of the cylinder from said chamber, an epicyclic piston within the cylinder and a supply valve mounted in the supply chamber, of means associated with said valve for causing one set of supply ports to be opened and another closed to effect the reversal of the motor.

14. In a rotary motor, the combination with a cylinder provided with exhaust ports and with separate sets of supply ports, and an epicyclic piston within the cylinder, of a supply chamber common to all of the supply ports, and a piston operated supply valve located in said chamber.

15. In a rotary motor, the combination with a cylinder, exhaust ports therefor and separate sets of supply ports, of an epicyclic piston in the cylinder, a supply chamber common to all of the supply ports, a supply valve located in said chamber, and a reversing valve designed to close one set of supply ports and open another set of said ports to effect the reversal of the motor.

16. In a rotary motor, the combination with a cylinder having exhaust ports, separate sets of supply ports, and a supply chamber common to all of the supply ports, of a piston in the cylinder, an epicyclic piston operated supply valve in the supply chamber, and a reversing valve interposed between the supply ports and the supply valve and movable to open one set of supply ports and to close another set of said ports.

17. In a rotary motor, the combination with a cylinder provided with exhaust ports, separate sets of supply ports, and supply and exhaust chambers located at its opposite

ends, of a piston within the cylinder, piston operated supply and exhaust valves in the supply and exhaust chambers respectively, and a reversing valve in the supply chamber.

18. In a rotary motor, the combination with a cylinder having exhaust ports, separate sets of supply ports, and a supply chamber through the peripheral wall of which the several supply ports open, of a piston within the cylinder, a reversing valve having the form of a disk located in the supply chamber and formed with a ported annular flange opposed to the peripheral wall of said chamber, and a piston operated supply valve of circular form also located in the supply chamber and having an apertured annular flange opposed to the annular flange of the reversing valve.

19. In a rotary motor, the combination with a cylinder having supply and exhaust ports, of a piston in the cylinder, a continuously rotating supply valve, a reversing valve, and means for shifting said valves simultaneously to reverse the motor.

20. In a rotary motor, the combination with a cylinder having supply and exhaust ports, of a piston therein, a supply valve continuously rotated by the piston, a reversing valve, and a lever for simultaneously shifting said valves to reverse the motor.

21. In a rotary motor, the combination with a cylinder provided with exhaust ports and with separate sets of supply ports, of a piston within the cylinder, a rotary reversing valve movable to open one set of supply ports and to close another set of said ports, a rotary controlling valve operated by the piston to control the supply of motive fluid through the supply ports which are left open by the reversing valve, and a lever arranged to shift said valves on their axes to reverse the motor.

22. In a rotary motor, the combination with a cylinder provided with exhaust ports and separate sets of supply ports, of a piston in the cylinder, a reversing valve arranged to open one set of supply ports and to close another set of said ports, a supply valve controlling the passage of motive fluid through the ports left open by the reversing valve, a cam mechanism for shifting one of said valves, and a rocker for shifting the other valve, to position said valves for the reversal of the motor.

23. In a rotary motor, the combination with a cylinder provided with exhaust ports and separate sets of supply ports, of a piston in the cylinder, a reversing valve arranged to open one set of supply ports and to close another set of said ports, a supply valve controlling the passage of motive fluid through the ports left open by the reversing valve, a cam mechanism for shifting one of said valves, a rocker for shifting the other valve, to position said valves for the reversal

of the motor, and an operating lever common to the cam mechanism and rocker.

24. In a rotary motor, the combination with a cylinder, of an epicyclic piston therein, a plurality of partitions dividing the cylinder into a series of compartments traversed in succession by the piston, means for supplying a motive fluid to one compartment to operate the piston, and means for exhausting 10 said motive fluid to another compartment to act upon the piston during another portion of its movement.

25. In a rotary motor, the combination with a cylinder, of an epicyclic piston therein, and a plurality of partitions serving in combination with the piston to divide the cylinder into a plurality of compartments, means for supplying motive fluid to each compartment in succession, and means for 15 directing the exhaust from one compartment to another compartment in advance thereof.

26. In a rotary motor, the combination with a cylinder, of a piston therein and a plurality of partitions serving in combination 25 with the piston to divide the cylinder into several compartments, and mechanism for causing the performance of the following functions: to-wit, first, the admission of motive fluid to a compartment, second, the 30 cut-off of the motive fluid supply to permit the use of the motive fluid expansively, and third, the passage of the motive fluid from said compartment to another in advance thereof.

35. 27. In a rotary motor, the combination with a cylinder, a piston therein, and a plurality of partitions dividing the cylinder into several compartments, of mechanism 40 for causing the following functions to be performed: to-wit, first, the supply of motive fluid to a compartment, second, the cut-off of the motive fluid supply to cause said fluid to be used expansively, third, the passage of a portion of the motive fluid in said 45 compartment to another compartment in advance thereof, and fourth, the complete exhaust or clearance of the compartment first named.

28. In a rotary motor, the combination 50 with a cylinder, a piston therein, and a series of partitions dividing the cylinder into several compartments traversed in succession by the piston, of mechanism for admitting exhaust fluid to one compartment to 55 effect the initial movement of the piston therein, and mechanism whereby, during the traverse of a compartment by the piston, said compartment will be first supplied with exhaust fluid from another compartment 60 and then with live or high pressure fluid.

29. In a rotary motor, the combination 65 with a cylinder, a piston therein, and a series of partitions dividing the cylinder into several compartments successively traversed by the piston, of mechanism whereby the

following functions will be performed in connection with each of the compartments in succession during the traverse thereof by the piston: first, the admission of exhaust fluid from another compartment, second, 70 the admission of live or high pressure fluid, third, the cut-off of the high pressure fluid supply to permit the use of the fluid expansively, fourth, the escape of a portion of the motive fluid to another compartment, and 75 fifth, the complete exhaust or clearance of the compartment.

30. In a rotary motor, the combination with a cylinder, a piston therein, and a series of partitions dividing the cylinder into several compartments traversed by the piston, each of said compartments being provided with supply and exhaust ports, of a piston operated supply valve controlling the supply 80 ports, and a separate valve for establishing 85 communication between the exhaust port of one compartment and the supply port of another.

31. In a rotary motor, the combination with a cylinder, a piston therein, and a plurality of partitions dividing the cylinder into several compartments traversed by the piston, supply and exhaust ports for each compartment, a supply valve controlling the several supply ports, and an exhaust valve, said 90 exhaust valve being arranged to place the exhaust port of one compartment in communication with the supply port of another compartment and to subsequently place said 95 exhaust port in communication with the 100 outer air.

32. In a rotary motor, the combination with a cylinder, a piston therein, and a plurality of partitions dividing the cylinder into a plurality of compartments traversed by the 105 piston, each of said compartments being equipped with supply and exhaust ports, of a piston operated supply valve controlling the supply ports, and a piston operated exhaust valve controlling the communication between the exhaust port of one compartment and the supply port of another. 110

33. In a rotary motor, the combination with a cylinder, a piston therein, and a plurality of partitions dividing the cylinder into several compartments, said cylinder being provided with supply and exhaust chambers at its opposite ends and each compartment being equipped with supply and exhaust ports, of a supply valve located in the supply 115 chamber and controlling the supply ports, and a combination valve located in the exhaust chamber and arranged to establish communication between the exhaust port of one compartment and the supply port of another and to subsequently close such communication and establish communication between the exhaust port and the interior of the exhaust chamber. 120

34. In a rotary motor, the combination 125

with a cylinder, a piston therein, and a plurality of partitions dividing the cylinder into several compartments, said cylinder being provided at its opposite ends with supply and exhaust chambers and each compartment having an exhaust port opening into the exhaust chamber and a supply port opening into the compartment and also opening into both the supply and exhaust chambers, a supply valve located in the supply chamber and controlling the passage of high pressure motive fluid through the supply ports, and an exhaust valve located in the exhaust chamber and arranged to control the communication between the exhaust port of each compartment and the supply port of the compartment next in advance thereof.

35. In a rotary motor, the combination with a cylinder, a piston therein, and a plurality of partitions dividing the cylinder into several compartments, said cylinder being provided at its opposite ends with supply and exhaust chambers and each compartment having an exhaust port opening into the exhaust chamber and a supply port opening into the compartment and also opening into both the supply and exhaust chambers, a supply valve located in the supply chamber and controlling the passage of high pressure motive fluid through the supply ports, and an exhaust valve located in the exhaust chamber and arranged to control the communication between the exhaust port of each compartment and the supply port of the compartment next in advance thereof, said exhaust valve also controlling the communication between the exhaust port of each compartment and the interior of the exhaust chamber.

40. 36. In a rotary motor, the combination with a cylinder, a piston therein, and a plurality of partitions dividing the cylinder into compartments, each compartment having an exhaust port and two supply ports, of a supply valve common to all of the supply ports.

37. In a rotary motor, the combination with a cylinder, a piston therein, and a plurality of partitions dividing the cylinder into several compartments, said cylinder being provided with exhaust ports, one for each compartment, and with two sets of supply ports, one port of each set opening into each compartment, of reversing valve mechanism arranged to open one set of supply ports and to close the other, and a controlling valve controlling the supply of motive fluid to the set of supply ports left open by the reversing valve mechanism.

38. In a rotary motor, the combination with a cylinder, a piston therein, and a series of partitions dividing the cylinder into compartments, said cylinder being equipped with an exhaust port for each compartment, two sets of supply ports, one port of each set opening into each compartment, and a

supply chamber in communication with two supply ports of both sets, of a reversing valve located in the supply chamber and movable to open one set of supply ports and to close the other, and a controlling valve 70 also located in the supply chamber and controlling the supply ports of that set left open by the reversing valve.

39. In a rotary motor, the combination with a cylinder, a piston therein, and partitions dividing the cylinder into compartments, said cylinder being equipped with an exhaust port for each compartment, with supply and exhaust chambers at its opposite ends, and with two sets of supply ports, all 80 of said ports opening into both the supply and exhaust chambers and one port of each set opening into each compartment of the cylinder, of reversing valve mechanism for closing one set of supply ports and opening 85 the other, a supply valve located in the supply chamber and controlling the passage of high pressure fluid to those supply ports left open by the reversing valve mechanism, and an exhaust valve located in the exhaust 90 chamber and arranged to establish communication between the exhaust port of one compartment and the supply port of a compartment in advance thereof, regardless of the direction of movement of the piston, and 95 to subsequently place the exhaust port in communication with the exhaust chamber to clear the compartment.

40. In a rotary motor, the combination with a cylinder, a piston therein, and a 100 plurality of partitions dividing the cylinder into compartments, said cylinder being equipped with an exhaust port for each compartment, supply and exhaust chambers, and two sets of supply ports, each supply 105 port opening into both the supply and exhaust chambers and one supply port of each set opening into each compartment of the cylinder, of reversing and supply valves located in the supply chamber, and a combination valve located in the exhaust chamber, said combination valve having the form of a hollow disk divided by a partition to form a compounding compartment and an 110 exhaust compartment, said exhaust compartment having slotted walls to establish communication between the exhaust ports of the compartments and the interior of the exhaust chamber, and said compounding compartment having a pair of supply ports arranged to be brought into apposition with the exhaust ports of the compartments and also having a pair of peripheral ports arranged to be brought into apposition with the supply ports, the arrangement of the 115 several valves being such that the motor may be operated in either direction and each compartment supplied first with exhaust fluid from another compartment and then with high pressure fluid from the supply 120

130

chamber during the traverse of the compartment by the piston.

41. The combination with a motor, a generating chamber associated therewith, 5 and valve mechanism controlling the supply of fluid to said chamber, of a supply valve for the motor arranged to control the supply of motive fluid to said motor from the generator, and an operating member common 10 to both the motor supply valve and the valve mechanism of the generator.

42. The combination with a motor and its supply valve, of a generating chamber, 15 means for supplying oil and water to said chamber, valves controlling the oil and water supply, and a single lever connected to the motor supply valve and also to the oil and water supply valves to simultaneously shift the same.

20 43. The combination with a motor equipped with a supply valve and a reversing

valve, of a generator arranged to supply motive fluid to the motor, valve mechanism controlling the supply of fluid to the generator, and a valve operating lever common 25 to the valve mechanism of the generator and to the supply valve and reversing valve of the motor.

44. In a rotary motor, the combination with a cylinder having supply and exhaust 30 ports, of a piston in the cylinder, a supply valve and a reversing valve, said valves being arranged concentrically, and means for shifting the valves simultaneously to effect the reversal of the motor.

In testimony, that I claim the foregoing as my own, I have hereto affixed my signature in the presence of two witnesses.

JOHN C. REUTER.
